UNITED STATES PATENT OFFICE.

JOHN DEWRANCE AND GEORGE HENRY WALL, OF SOUTHWARK,
ENGLAND.

WATER-LEVEL INDICATOR.

SPECIFICATION forming part of Letters Patent No. 739,994, dated September 29, 1903.

Application filed March 10, 1902. Serial No. 97,575. (No model.)

To all whom it may concern:

Be it known that we, JOHN DEWRANCE and GEORGE HENRY WALL, subjects of the King of Great Britain and Ireland, residing at 165 5 Great Dover street, Southwark, in the county of Surrey, England, have invented new and useful Improvements in the Construction and Working of Water - Level Indicators for Steam-Generators and the Like, of which the following is a specification.

This invention relates to an improved method of constructing and working water-gages provided with automatic valves, our object being to enable a blow-off to be effected 15 through the upper arm and gage-glass and through the lower arm, respectively, at successive stages in the complete operation of manual appliances, which may be arranged to work either reciprocatively or rotatively.

The accompanying drawings illustrate various constructions of water-level indicators embodying our improvements.

In Figures 1 to 5 the arrangement enables a blow-off to be effected through the lower and 25 upper arms consecutively by a rotative movement of a single hand - wheel without interference with the shut-off valves, Fig. 1 being a vertical section, Fig. 2 an exterior elevation, and Figs. 3, 4, and 5 transverse sections 30 taken, respectively, on the lines $x - x$, $y - y$, and $z - z$ in Fig. 1. Fig. 6 is a vertical section, and Fig. 7 an elevation, of a construction which enables a blow-off to be effected by means arranged to work reciprocatively, Figs. 8 and 9 being transverse sections taken, respectively, 35 on the lines $x' - x'$ and $y' - y'$ in Fig. 6.

Water - gages as commonly constructed comprise two arms adapted for attachment to the boiler-front and are furnished with cocks 40 whereby the steam and water respectively may when necessary be shut off. Between the two arms a gage-glass is mounted, and the lower arm is in addition provided with a blow-through cock. When it is desired to provide 45 against the escape of steam or water in the event of the gage - glass bursting or being broken, one arm or each arm is furnished with a ball-valve, which under normal conditions is off its seat, but which upon fracture of the 50 gage-glass instantly seats itself and intercepts the escape of steam or other fluid under

pressure. When using a water-gage of this description, it is necessary when blowing through the upper arm and gage-glass not simply to close the cock in the lower arm and open the 55 blow-through cock, but to adopt some means for preventing the ball-valve at the upper end of the gage-glass seating or for displacing it if seated.

It has been proposed to construct water-level indicators having an automatic valve both in the upper and in the lower arm and provided with unseating appliances arranged in such a manner that at successive stages in a complete operation of the blow-off mechanism a blow takes place through the normal working passages in the lower and in the upper arms, respectively.

According to our improved method of construction instead of manipulating the automatic valve in the lower arm so as occasionally to hold it off its seat we arrange this valve so as to be permanently automatic, and we fit the same arm with a supplementary valve, which serves to open or to close the 70 water - passage between the boiler and the lower gage-glass holder. The upper arm of the gage-glass is furnished with an automatic valve, arranged in conjunction with an anti-seating or an unseating appliance, which may 75 be either rotative or reciprocative in its action, but which in any case forms part of or is in connection with the directing-valve pertaining to the lower arm. The blow-off mechanism may assume the form of a rotative 80 spindle or rod A, which in the lower arm is arranged as a two-way cock a and in the upper arm as an automatic-valve carrier a' , formed as a valve unseating or antiseating appliance. Referring to Figs. 1 to 5, the cock 90 a in one position of the rod A opens communication with the boiler through the bore or passage b^2 of the lower arm and the longitudinal passage a^{15} and lateral outlet-passage a^{16} to the blow-off orifice a^{17} . In another position of the said rod communication is 95 opened with the boiler by way of the gage-glass and bore or passage b^3 of the upper arm. The ports through which communication is established will, however, be readily comprehended without further reference to the 100 drawings.

In view of the desirability of rendering the position of the mechanism more apparent at a glance the blow-off mechanism may be arranged upon the reciprocatative principle and 5 be worked by means of a hand-lever, the normal position for which is well defined.

A water-level indicator of the kind last above referred to is illustrated in Figs. 6 to 9. The directing-valve in the lower arm may 10 assume the form of a cylindrical rod A', formed with one through-passage a² for communicating directly between the boiler and the lower gage-glass holder, a lateral recess a³ for communicating between the boiler and a chamber 15 b¹, a second lateral recess a⁴ for communicating between the lower extremity of the gage-glass and the chamber b¹, and, finally, a longitudinal passage a⁵, having a lateral inlet a⁶ and a terminal outlet a⁷ to the blow-off orifice 20 a⁸. It will be seen that by causing the rod A' to assume certain positions the blow-off orifice a⁸ is placed in communication with the boiler either through the lower arm or through the gage-glass and the upper arm. The directing- 25 valve and the blow-through cock may, however, be arranged as separate devices and connected together in any convenient manner for the purpose of combined action. The automatic valve a⁹ is preferably supported in 30 the chamber a¹⁰ by means of ledges a¹¹, a finger a¹² in the chamber a¹⁰ assisting the exit from the said chamber of the ball a⁹ upon the withdrawal of the plug a¹³. The unseating or antiseating appliance in the upper arm 35 may consist of a spindle or stem a', working through a stuffing-box a⁰ and serving either to unseat the automatic valve a⁹ or to prevent its seating when it is desired to effect a blow-off through the upper arm and gage- 40 glass. A suitably-mounted hand-lever C is arranged at some intermediate point between the upper and lower arms. This lever in the construction illustrated is pivoted in the upper end of a link C', the lower end of the latter being pivoted in a lug C², formed on the 45 lower arm. The lever is connected, by means of the stud C³, with the rod A', the spindle or stem a', comprising the unseating or antiseating appliance, being attached to the upper 50 extremity of the rod A' by means of the stud a¹⁴.

The operation is as follows: Upon lifting the hand-lever C the first effect is to carry the through-passage a² in the rod A' past the 55 bore b² of the lower arm and open communication with the chamber b¹ and the lower arm by way of the lateral recess a³. The lateral inlet a⁶ being now open to the chamber b¹ a blow through the lower arm is effected. As 60 the hand-lever C is moved to its extreme position (upward) the communication with the boiler through the lower arm is closed, the full portion of the rod A' beneath the lateral recess a³ coming opposite the bore b², which 65 leads to the boiler. Communication with the latter is, however, opened by way of the lateral recess a⁴, the gage-glass, and the bore b³

in the upper arm. The automatic valve a⁹ will now assume the position shown in dotted line in Fig. 6, wherein it is held by the spindle a'.

If the apparatus be inverted, what has been referred to as the "lower arm" becomes the upper arm, and vice versa.

What we claim as our invention, and desire 75 to secure by Letters Patent, is—

1. A water-level indicator having upper and lower arms for communicating with the steam-generator or other vessel provided as to its upper arm with an automatic valve and with an 80 appliance adapted for temporarily preventing the said valve seating, and provided as to its lower arm with an automatic valve and with a controlling-valve adapted for opening communication between the boiler and the blow-off, first through the lower arm, and secondly 85 through the upper arm and gage-glass, whereby at successive stages in a complete operation of the apparatus, a blow-off is effected through the normal working passages in the 90 lower and upper arms respectively, substantially as herein described.

2. A water-level indicator having upper and lower arms for communicating with the steam-generator or other vessel provided as to its upper arm with an automatic valve and with an 95 appliance adapted for temporarily preventing the said valve seating, and provided as to its lower arm with an automatic valve and with a controlling-valve adapted for opening communication between the boiler and the blow-off, first through the lower arm, and secondly 100 through the upper arm and gage-glass; the two-way controlling-valve in the lower arm and the valve-antiseating device in the upper 105 arm being coupled together for joint manual operation and in such relation to one another that, at successive stages in a complete operation of the apparatus, a blow-off is effected through the normal working passages in the 110 lower and upper arms respectively, substantially as herein described.

3. In an automatic-valve-fitted water-level indicator, the herein-described means for controlling communication between the boiler 115 and the "blow-off," same comprising a cylindrical rod formed as a two-way valve in the lower arm and as an unseating or antiseating appliance in the upper arm in combination with means for operating the said rod; the 120 whole being arranged in such a manner that, at successive stages in a complete operation of the apparatus, a "blow-off" takes place through the normal working passages in the lower and upper arms respectively, substantially 125 as herein described.

4. In an automatic-valve-fitted water-level indicator, the herein-described means for controlling communication between the boiler and the "blow-off," same comprising a cylindrical rod formed, as to the lower arm, with a through-passage, communicating with the 130 normal working passage in the said arm, a longitudinal passage connecting the through-

passage with a lateral outlet and, as to the upper arm, as an automatic valve-carrier formed as a valve unseating or antiseating appliance, and provided at its outer extremity with a hand-wheel or equivalent means whereby a rotative movement may be imparted to the said rod, substantially as set forth.

5 In testimony whereof we have signed our

names to this specification in the presence of two subscribing witnesses.

JOHN DEWRANCE.
GEORGE HENRY WALL.
